TIMING DEVICE FOR FOLDING MACHINES

Thomas J. Doran, Cleveland Heights, Ohio, assignor to The American Laundry Machinery Company, Cincinnati, Ohio, a corporation of Ohio

Application December 26, 1947, Serial No. 793,806

5 Claims. (Cl. 270—80)

1

The invention relates to a novel and improved timing device for the performance of an operation at a preselected point on a traveling article, and it relates more specifically to a timing device for performing a proportional folding operation on flat work such as paper sheets, or laundry towels, sheets or the like.

Electronic time delay relays are now known in the art for effecting proportional folding operations. For example, in U. S. Patent Number 2,374,779, issued May 1, 1945, to John E. Preston, there is disclosed electronic time delay means involving a time control responsive to discharge of a capacitor at different rates over different successive time periods, whereby a folding element, responsive to completion of such discharge, effects one or more proportionate folds in each of a succession of moving articles, permissibly of varying lengths. By means of Preston's control, each such article can be automatically folded at its mid point, or at two points such as the half and quarter length points, etc., or at other proportional intervals regardless of variations in length, within a permissive range. Certain embodiments of the Preston control are dependent upon the discharge of one or more capacitors before the execution of the folding operation.

As may be determined from an examination of the aforementioned Preston U. S. Patent Number 2,374,779, an article which is to be folded for example at its mid point, itself initiates discharge of the control capacitor when its leading edge operates a trip in the path of travel. The duration of time delay between such initiation of discharge and completion of the discharge to produce the desired operation is varied by the fact that the capacitor is permitted to discharge at different rates depending on article length, the change from a slow rate to an accelerated rate, for example, being initiated by passage of the trailing edge of the article past a trip in the path of travel. Fig. 10 of the Preston patent discloses electronic means in an electrical circuit whereby a single proportionate fold may be effected in a moving article such as a towel or sheet, regardless of length, and whereby a single control trip is sufficient to sequentially initiate both the first and second discharge rates of the capacitor. In this Preston embodiment, the leading edge of the article intercepts the trip and initiates discharge at the first rate and the trailing edge of the article, on leaving, the same trip, initiates discharge at a second rate, the proportioning of the time occupied by each rate of discharge being thus responsive to the article length itself.

2

It is apparent, however, that in the embodiment shown in Fig. 10 and other figures of the aforesaid Preston patent, if the leading edge of a succeeding article intercepts the trip before completion of the operation on the preceding article, it not only nullifies the proper timing on the preceding article, but the capacitor is not permitted to again recharge. In this event the operation is not properly performed on two successive articles in the moving line. For successful operation of this and certain other of the embodiments in the aforesaid Preston patent, sufficient time must elapse after operation of the control trip, not only to permit completion of the first operation but also to allow sufficient additional time for recharging of the capacitor or capacitors for the second operation. While the time required for such recharge is only momentary, a train of articles moves relatively rapidly with the conveying means, and successive articles must be spaced far enough apart to permit discharge and recharge before each succeeding article operates the trip.

An object of the present invention is to provide time control means permitting quite minute spacing between each of a plurality of articles in succession in a moving line, while insuring an effective and accurate proportioned operation on each article. By the term "proportioned" or "proportional" as used herein, I mean an operation at the half point, or quarter point, or elsewhere fractionally of the article length.

A further object of the present invention is to provide means such as specified in the last preceding paragraph, whereby two separate and distinct timing operations on two successive articles can take place with a mutual chronological overlap, so that at least parts of both said timing operations may proceed simultaneously.

40 A further object of the invention is to provide an electronically controlled laundry flatwork folder comprising a pair of folding control units, each unit being complete and distinct, and being individually adapted to control the proportioned folding of an article, in conjunction with article folding means, and selector means energized successively by passage of each of several articles on a conveyor, said selector means being adapted to render said folding means responsive, alternately, first to one said control unit, and then to the other said control unit.

Further objects of the invention are in part obvious, or will become apparent upon a study of the following specification in conjunction with 55 the accompanying drawings in which

Fig. 1 is a schematic showing of the essential elements of a machine for executing a single fold in a piece of laundry flat work;

Fig. 2 is a representation, partly diagrammatic and partly schematic, showing one embodiment of my invention, and

Fig. 3 shows somewhat conventionally, one embodiment of a snap-over device such as is used herein.

As representative of an operation to be performed, I have selected the folding of a piece of laundry flatwork at a point proportionate to its length, for example in the middle. It will be obvious as the description proceeds that the inventive concept may be utilized to perform other than folding operations at proportioned points on a series of moving articles.

Referring to the folding machine as shown schematically in Figs. 1 and 2, each towel in a series to be folded is advanced from right to left on an endless conveyor 10. Each towel in succession passes a "trigger" zone, and its leading edge interrupts electrical contacts through three trips 11, 12 and 13 so as to open respective electrical circuits. When the trailing edge passes the trips, the circuits are again closed. From the trips each towel advances to a folding zone where it is folded by mechanism responsive to trip operation, and later to be described. Trip 11 is a selector trip for alternately selecting one or the other of two electronic control units A and B. Trip 12 cooperates with trip 11 in utilizing unit A for the execution of a timed folding operation on a first towel, and trip 13 cooperates with trip 11 in utilizing unit B for a like operation on the next towel. In the embodiment shown the three trips are arranged in a line transverse to the direction of travel of the towel, so as to be operated substantially simultaneously.

By means of this arrangement, and the circuits to be later described, if a time control unit A is timing a towel for an ultimate folding operation, and a second towel follows closely, it will not interfere with the timing operation on the first towel since unit B is then selected to come into operation and take up the task of timing the folding operation on the second towel. As will further appear, when the control is based upon the complete discharge of a condenser prior to operation of the folding means, and subsequent recharge for another operation, the use of two complete and distinct timing units, operating alternately, allows each unit ample time for condenser discharge and recharge before it is again called upon to initiate another timing operation. It will be apparent that operation of the control units may be based upon timing means other than capacitance discharge, while still embodying my invention whenever the advantages hereinabove enumerated are obtained by the use of alternately energized units.

Selector trip 11, when permitted to close by passage of the trailing edge of a towel, energizes a snap-over arrangement in housing 15 responsive to the closing of a circuit from L₁ to L₂ so as to throw armature 16 across the gap between the "a" and "b" positions. The operation of this snap-over device will be more fully explained later in conjunction with Fig. 3. It will be understood that when in "a" position it is in operative relationship with control unit A, and when in "b" position it is in operative relationship with control unit B. It will also be further understood that interception of trip 11 by the leading edge of a towel merely breaks the electric power supply

to the snap-over means 15 and causes no operation of the snap-over mechanism. It will be further understood that armature 16 reverses its position each time the trailing edge of a towel passes trip 11.

The folding mechanism comprises a folding blade 18 operated by energization of a solenoid within housing 19. Energization of the solenoid produces movement of an armature (not shown) 10 operatively linked to the folding blade. Each stroke of the folding blade closes a micro switch 20 in circuit with a switch-reversing arrangement indicated at 21 and energized by a circuit L₁—L₂ which throws the switch armature 22 from contact a to contact b or vice versa. Switch armature 22, and switch armature 16 previously described, mutually cooperate as will appear.

Since unit A and unit B are identical in structure, description of one will suffice, with special reference to Fig. 2.

Tubes 25 and 26 are separate heater type A. C. triodes, grid-controlled to pass anode-cathode or plate-current when the grid bias is within a specific range, but to cut off the plate current 25 when the bias exceeds a critical or cut-off point.

The grid of tube 25 is normally biased from the secondary of the transformer 28, through resistor 29, to permit plate current to pass so as to energize relay coil 30. When trip 12 is in its 30 normally closed position, however, an excess grid bias is applied to tube 25 from voltage divider 31 through conductors 32 and 33, trip 12, conductors 34, 35, and 36, resistor 29 to the grid of tube 25 and from the grid through the cathode and conductor 37 to the voltage divider. This grid-cathode current flows only during the half cycle when the grid is positive with respect to the cathode. This cuts off plate current in tube 25 and deenergizes relay 30. Opening and closing of 40 trip 12 by the leading and trailing edges, respectively, of a moving towel therefore produces, respectively, energization and deenergization of relay coil 30.

A similar result is produced on relay coil 30a, 45 in unit B, by operation of trip 13, except when trip 13 is shunted by armature 16, as shown.

The grid of tube 26 is at normal bias when capacitor 39 is fully discharged, by means to be later described. When thus normally biased tube 50 26 passes plate current from the secondary wiring 40 of transformer 28 through conductors 41 and 42, relay 43, conductors 44 and 45, plate to cathode of tube 26, and conductors 46, 47, and 37 back to secondary wiring 40. Energization and de-energization of relay coil 43 is therefore responsive, respectively to the discharged or charged condition of capacitor 39, since when the capacitor is charged it overbiases the grid of tube 26 to terminate plate current to relay 43.

60 A cycle of operations involving the performance of a folding operation on two successive towels in a moving row will now be described.

To start the cycle, assume that the machine has been shut down, that capacitor 39 is fully 65 discharged, that switch armature 16 is in "b" position (as shown) and that switch armature 22 is in "a" position, as shown. The reason for switch armature 16 being in "b" position will appear as the description of the cycle proceeds. 70 The current supply from the line is now turned on to energize transformer 28 and heat the filaments of all tubes. Since trip 12 is closed, tube 25 is overbiased, and armature 50 of relay 30 is in its "b" position as shown. Since capacitor 39 75 is discharged, tube 26 is normally biased, and

relay 43 is energized by passage of plate current, placing its coupled armatures 51, 52 and 53 in their "a" positions.

Under the conditions just outlined, as soon as the line switch is turned on, capacitor 39 begins to charge from voltage divider 31 in the secondary of transformer 28 through conductors 37 and 47, cathode and grid of tube 26, capacitor 39, conductors 55 and 56, armature 53 in "a" position, and conductor 57 to the voltage divider. The capacitor 39 rapidly acquires maximum charge, and consequently exceeds the tube-operating bias value of tube 26, so that tube 26 is blocked, and relay 43 would normally be de-energized. The relay remains energized, however, because of a maintaining circuit including trip 12 and relay armature 52 as follows; from the transformer secondary through conductors 41 and 42, relay coil 43, conductors 44 and 38, armature 52, conductors 54, 35, and 34, trip 12, and conductors 33 and 32, so that the relay coil 43 remains energized, armature 53 remains in "a" position, and the charging effect is maintained.

Assume that a towel T approaches from the right on conveyor 10, and its leading edge simultaneously intercepts trips 11, 12 and 13. The opening of trip 12 breaks the maintaining circuit of relay 43, and its armatures all fall to their "b" position. Opening of trip 12 also removes the excess bias of tube 25, as hereinbefore explained, the tube passes plate current, relay 30 is energized, and armature 50 moves to "a" position. Since the charging of capacitor 39 was terminated at armature 53 when relay 43 was de-energized by opening of the maintaining circuit, capacitor 39 in unit A immediately begins to discharge, although capacitor 39a in unit B remains under charge since the maintaining circuit for unit B is still maintained by its shunt through armature 16 in "b" position, even though trip 13 has been opened by the towel's leading edge.

Capacitor 39 in unit A, immediately upon interception of trip 12 by the leading edge of the towel as aforesaid, begins to discharge through the following circuit; from capacitor 39 through conductors 55, 58 and 59, armature 50 in "a" position, resistor 61, and conductor 62 to capacitor 39. Resistor 61 has a relatively high resistance value, and the capacitor charge leaks off at a relatively slow rate, towel advance in the meantime continuing. When the trailing edge of the towel leaves trip 12, the trip closes, again imposing an overbias on tube 25 so that relay 30 is de-energized, armature 50 falls to "b" position, but capacitor discharge as above outline continues, except that it now proceeds through resistor 63 instead of resistor 61. Resistor 63 is of lower resistance than resistor 61, so that discharge proceeds at an accelerated rate. The relationship of the combined slow and fast discharges is such that it produces the desired proportionate measurement of the towel according to the principles set forth in the aforesaid Patent U. S. Patent No. 2,374,779.

As soon as capacitor 39 is discharged to a point where its grid biasing effect is no longer of sufficient value to overbias the grid of tube 26, the tube passes plate current, relay 43 is energized, its armatures, including armature 51, move to "a" position, and the folding blade solenoid is energized as follows: from L₁ through conductor 60, armature 51 in "a" position, conductor 64, armature 22 in "a" position, conductors 65 and

66, folding blade operating device 19, and conductor 67 and 68 to L₂. A folding operation is thereupon performed on the towel. Operation of the folding blade closes switch 20, energizes device 21, and results in the movement of switch armature 22 to the "b" position, adapted to next cooperate with a folding operation controlled by unit B. Snap switch controls 15 and 21 are identical, and will be more fully described later.

As the trailing edge of the towel passed trip 11, the snap-over device 15 was energized, as already understood, throwing switch armature to its "a" position and thereby supplying a shunt circuit for trip 12 so as to permit capacitor 39 to continue discharge at "status quo" rate. This shunt circuit avoids the inherent defect in known prior devices. In said prior devices of the present general character, if the leading edge of a second towel broke the control trip contact (in this case trip 12) before discharge of the control capacitor (in this case capacitor 39 of unit A) was completed, the discharge reverted to the undesired low rate, thereby throwing the whole operation out of accurate sequence. In the present instance this is prevented by the provision of two distinct control units, in conjunction with selector trip 11 and reversible switch armature 22, as will appear.

Assume that a second towel approaches on the conveyor, and its leading edge intercepts trips 11, 12 and 13 while the preceding operation by unit A is still in progress, switch armature 16 being now in "a" position.

Breaking contact at trip 12 by the second towel has no effect on the operation of unit A (which is still operating on the first towel) because armature 16 is now in the "a" position, and maintains the over bias on tube 25 through conductors 32 and 70, armature 16 in "a" position, and conductors 71, 35, and 36, resistance 29, grid and cathode of the tube and conductor 37. Relay 30 remains de-energized, armature 50 remains in "b" position and discharge continues at the accelerated rate.

Breaking contact at selector trip 11 by the second towel likewise has no effect on the operation of unit A because the selector trip operates the snap-over device 15 only when contact is made at trip 11.

However, when the second towel intercepts trip 13, and breaks contact at that point, it begins discharge of capacitor 39a in unit B by breaking its maintaining charging circuit, as will be fully understood upon consideration of what has already been described with respect to inception of operation of unit A. It will be evident therefore that discharge of capacitors 39 and 39a is now taking place simultaneously, and travel of the first and second towels is being timed simultaneously, but by different units.

At about this time in the progress of the cycle, capacitor 39 in unit A discharges past the critical bias point, and the first towel is folded, at which time operation of folding blade 18 throws switch armature 22 to the "b" position so as to leave it in the circuit associated with armature 51a of unit B, where it will be adapted to respond next to the discharge of capacitor 39a of unit B.

When the trailing edge of the second towel passes trips 11, 12 and 13, it leaves them in the position in which they were at the beginning of the herein described cycle of activity, since contact at selector trip 11 again throws armature 16 back to the "b" position. Folding of the second towel also throws switch armature 22 to its "a"

position. When a third towel goes through, it energizes the circuits previously energized by the first towel, and thus alternate towels will be operated on respectively alternately by units A and B.

Another advantage to the use of two alternating units, as shown, is that the interposition of an extremely short article among a succession of relatively long articles, or vice versa, does not disturb the timing sequence. The timing sequence might be disturbed if two extremely short articles follow a maximum length article on the conveyor. This condition is not usually met, and the apparatus will perform satisfactorily if the minimum length article to be folded is not smaller than about one third of the maximum length article. With this in mind the sequence of long and short articles, in any order, is immaterial. This numerical limitation is dependent on several factors such as the spacing between the trips and the folding blade, the total charge in the charged capacitor, and the respective rates of the capacitor discharges.

The reference numerals in unit B are identical with the numerals applied to respectively corresponding parts in unit A, except that all numerals in unit B are accompanied by the suffix *a*. To simplify the wiring circuits as far as reasonably possible, we have shown two transformers 28 and 28a with their respective primary and secondary circuits. Obviously one transformer would be used in practice, with any convenient or necessary number of secondary taps. The secondary taps F₁—F₂ on transformer 28 energize the filaments of tubes 25 and 26. In Fig. 2 the snap-over devices 15 and 21 are illustrated merely schematically. Such devices for reversing an element position at each energization but not at each de-energization, are available commercially, and their specific structure forms no part of the present invention. For completeness of disclosure, however, one such device is shown in Fig. 3, and its operation will now be briefly described.

The device comprises a pair of axially aligned, spaced solenoids 75 and 76 provided with a pair of armatures 77 and 78 united by a rod 79. As will appear, the solenoids are energized alternately, so as to move armatures 77 and 78 back and forth. The mid point of a toggle linkage 80, 81 is pivoted at 82 on rod 79. Link 81 also has an intermediate pivot point 83 which is fixed with respect to the solenoids. The corresponding point 84 is linearly movable with respect to pivot 83, and a tension spring 85, having a fixed end at 83, and a movable end at 84, tends to increase the angularity between the links 80—81. The device therefore constitutes an over-center snap action mechanism, and, in the position shown, if solenoid 75 is energized while solenoid 76 is de-energized, armature 77 will be moved downwardly into solenoid 75, causing over-center operation of the linkage, and reversal of the position of switch armature 16, which is carried on the end of link 81.

Alternate energization of solenoids 75 and 76 is accomplished as follows. Closure of selector trip 11, as by passage of the trailing edge of a towel closes an electrical circuit from L₁ through conductor 87, contacts of switch 88 through armature 89 on the end of link 80, conductor 90, solenoid coil 75, conductors 91 and 92, relay armature 93, and conductors 94, and 95 to L₂. Energization of solenoid coil 75 produces reversal of the over-center linkage, and consequent travel of

the switch armature 89 along connector strip 96 towards switch 97. As armature 89 passes the mid point of its travel, it momentarily establishes a circuit connection between strip 96 and a terminal 98 so as to complete an energizing circuit for relay coil 99 as follows; from L₂ through conductor 95, relay coil 99, conductors 100 and 101 to terminal 98, thence through armature 89 to strip 96, conductor 87, and trip 11 to L₁. Energization

10 of relay coil 99 attracts linked armatures 93 and 102 with the following results.

Armature 102 moves from its "b" position to its "a" position to set up the following maintaining circuit for relay coil 99; from L₂ through conductor 95, relay coil 99, conductors 100 and 103, armature 102 in "a" position, conductor 104, conducting strip 96, conductor 87, and closed trip 11 to L₂. As a result of relay coil 99 being energized armature 93 has moved from its "b" to its 20 "a" position, breaking to circuit to solenoid 75 so as to de-energize it, both solenoids 75 and 76 being at the present time de-energized.

In the meantime armature 89 on link 80 comes to rest at switch 97, at which point it is in position to energize solenoid 76 at a proper position in the cycle, as will appear.

When the leading edge of a second towel intercepts trip 11, it breaks the maintaining circuit for relay coil 99 and armatures 93 and 102 fall to their "b" positions. Interception of trip 11 has no other effect at this time.

When the trailing edge of the second towel passes trip 11, permitting it to again close, solenoid 76 is now energized through a circuit from L₁ through trip 11, conductor 87, strip 96, armature 89 bridging switch contacts 97, conductor 106, winding of solenoid 76, conductors 107 and 92, armature 93 in "b" position, conductors 94 and 95 to L₂.

40 Energization of solenoid 76 again snaps the linkage 80—81 over-center, causing armature 89 to be carried back towards switch 88. At the mid point of its travel it establishes an energizing circuit for relay 99, as before, and relay 99 sets up 45 its own maintaining circuit while solenoid 76 is de-energized by a circuit break at armature 93.

By the use of a device of this nature, each time the circuit is closed at trip 11, by passage of the trailing edge of an article, switch armature 16 50 on the end of link 81 reverses its position, but nothing happens when the circuit is broken at trip 11 by the leading edge of an article.

In the circuits shown in Fig. 2, switch armatures 16 and 22 bear a certain phase relationship 55 to each other to the extent that when armature 16 starts in the "a" position, armature 22 should start in the "b" position. If, one or other armature should accidentally become reversed so as to be out of phase, with the other the first article 60 thereafter passing through will reverse armature 16 but will not be folded. Thereafter both armatures will be in proper phase for the second and all subsequent articles.

The trips 11, 12 and 13 have been schematically 65 illustrated in Fig. 2 as physically distinct from each other, but all three trips are opened by the leading edge of the moving article, and all three close when the trailing edge of the article leaves them. It will be apparent to those skilled in the art that a single trip could be arranged to carry three sets of electrical contacts, one such set controlling the circuit to selector 15, and the other two sets serving the respective timing circuits to units A and B. In this specification, and the appended claims, the term "trip" while compris-

ing the conventional device heretofore well known in the art, likewise include any other arrangement wherein a pair of electrical circuit terminals are separated, or moved into contact, responsive to movement of the article.

What I claim is:

1. Apparatus of the character described for effecting a proportionate fold in each of a series of laundry flatwork articles moving in longitudinally spaced relationship along a path, comprising a folding device, a pair of substantially identical time delay units effective upon said folding device, each unit being independently adapted to control operation of said folding device, a first timing trip, a second timing trip, and a selector trip, all said trips being disposed adjacent each other in said path whereby to be intercepted by a moving article, electrical circuit means operatively connecting the first said timing trip to one time delay unit, and the second said timing trip to the other time delay unit, switch means responsive to operation of said selector trip by a moving article, said switch means being effective alternately, upon the electrical circuit for one said unit and the electrical circuit for the other said unit, whereby interception of the first said timing trip and the selector trip by a moving article institutes a timed control operation by one said time delay unit, and interception of the second said timing trip and the selector trip by the next succeeding moving article institutes a timed control operation by the other said timing unit.

2. Apparatus of the character described for effecting a proportionate fold in each of a series of laundry flatwork articles moving in longitudinally spaced relationship along a path, comprising folding means, a first time control unit a second time control unit, each unit being independently adapted to cause operation of said folding means, first and second folding circuits respectively operatively connecting said first and second time control units with said folding means, a folding selector switch responsive to operating movement of said folding means, and effective alternately upon said first and second folding circuits whereby to render said folding means responsive, alternately to said first and second time control units, a first timing trip, a second timing trip, and a timing selector trip, all three said trips being disposed adjacent each other in said path ahead of said folding means whereby to be intercepted by each moving article, first and second timing circuits respectively connecting the first said timing trip to the first said time control unit, and the second said timing trip to the second said time control unit, switch means responsive to said timing selector trip and effective alternately upon said first and second timing circuits whereby interception of the first said timing trip and the selector trip by a moving article institutes a time control operation by one said time control unit, and interception of the second said timing trip and the selector trip by the next succeeding moving article institutes a time control operation by the second said time control unit.

3. Apparatus of the character described for effecting a proportionate fold in each of a series of laundry flatwork articles moving in longitudinally spaced relationship along a path, comprising folding means, a first time control unit, a second time control unit, each unit being independently adapted to cause operation of said folding means, first and second folding circuits re-

spectively operatively connecting said first and second time control units with said folding means, a folding selector switch responsive to operating movement of said folding means, and effective alternately upon said first and second folding circuits whereby to render said folding means responsive, alternately to said first and second time control units, a first timing trip, a second timing trip, and a timing selector trip, all three said trips being disposed adjacent each other in said path ahead of said folding means whereby to be intercepted by each moving article, first and second timing circuits respectively connecting the first said timing trip to the first said time control unit, and the second said timing trip to the second said time control unit, switch means responsive to said timing selector trip and effective alternately upon said first and second timing circuits whereby interception of the first said timing trip and the selector trip by a moving article institutes a time control operation by one said time control unit, and interception of the second said timing trip and the selector trip by the next succeeding moving article institutes a time control operation by the second said time control unit, said folding blade selector and said timing selector having a definite positional phase relationship to each other whereby, when the first said timing unit completes a timing operation responsive to interception of the first said timing trip and selector trip, said folding selector is in suitable position to close said first folding circuit with consequent operation of said folding means, and when the second said timing unit completes a timing operation responsive to interception of the second said timing trip and the said selector trip, said folding selector is in suitable position to close said second folding circuit with consequent operation of said folding means with respect to the next succeeding article.

4. Apparatus of the character described including operation-performing means for the execution of a timed operation on each of a series of spaced, moving articles, comprising a first time control unit and a second time control unit, each such time control unit having, as an element thereof, an electrical capacitor, each said capacitor having its respective electrical control circuits, and being adapted by controlled change in the charge thereof to control the said timed operation, and each such control unit being responsive to article travel past a control zone, selector switch means located in said control zone, and responsive to passage of each article past said control zone, said selector switch means being operatively effective upon said electrical control circuits and thereby upon the two said time control units in turn, so as to initiate a complete timed operation, first by the first said time control unit on one article in said series, and next by the second said time control unit on the next article in said series, each such time control unit having respective electrical circuit connections with said operation-performing means whereby completion of the timed operation by each time control unit in turn is effective upon said operation-performing means to produce operation thereof.

5. Apparatus of the character described including operation-performing means for the execution of a timed operation on each of a series of spaced, moving articles, comprising a first time control unit and a second time control unit, each such time control unit having, as an element thereof, an electrical capacitor, each said capaci-

11

tor having its respective electrical control circuits, and being adapted by controlled change in the charge thereof to control the said timed operation, and each such control unit being responsive to article travel past a control zone, selector switch means located in said control zone, and responsive to passage of each article past said control zone, said selector switch means being operatively effective upon said electrical control circuits and thereby upon the two said time control units in turn, so as to initiate a complete timed operation, first by the first said time control unit on one article in said series, and next by the second said time control unit on the next article in said series, a second selector switch means having respective electrical circuit connections with each time control unit, and also with said operation-performing means, said second selector switch being operatively responsive to operation of said operation performing means

5

10

15

20

12

so as to close the circuit first to one said time control unit on one operation of said operation-performing means, and then to close the circuit to the other said time control unit on the next operation of said operation-performing means, whereby completion of the timed operation by each time control unit in turn is effective upon said operation-performing means to produce operation thereof.
